EARTHMOVING SCRAPER PUSH FRAME

George A. Fisher and Bennett N. Waddell, Joliet, Ill.,
assignors to Caterpillar Tractor Co., Peoria, Ill.

Filed Mar. 27, 1974, Ser. No. 455,493

Term of patent 14 years

Int. Cl. D15—04

U.S. Cl. D40—5

FIG -1-

FIG -2-

FIG. - 3 -

FIG. - 4 -

FIG. 5.

FIG. 6.

FIG. 1 is a side elevational view of an earthmoving scraper push frame embodying our new design.

FIG. 2 is a side elevational view thereof of the side opposite to that shown in FIG. 1.

FIG. 3 is a front elevational view thereof.

FIG. 4 is a rear elevational view thereof.

FIG. 5 is a top plan view thereof.

FIG. 6 is a bottom plan view thereof.

We claim:

The ornamental design for an earthmoving scraper push frame, substantially as shown.
